UNITED STATES PATENT OFFICE.

JOSEPH HAVLINA, OF MOSINEE, WISCONSIN.

WATER-MOTOR.

1,304,972.

Specification of Letters Patent. Patented May 27, 1919.

Application filed March 8, 1919. Serial No. 281,370.

To all whom it may concern:

Be it known that I, JOSEPH HAVLINA, a citizen of the United States, residing at Mosinee, in the county of Marathon and 5 State of Wisconsin, have invented a new and useful Water-Motor, of which the following is a specification.

This invention relates to a water motor, one of its objects being to provide an arrangement of turbines each of which is connected to a drive shaft and can be operated whenever desired at the same time with or independently of the other turbines.

Another object is to provide a mechanism 15 of this character which is simple, durable and efficient and can be controlled readily.

With the foregoing and other objects in view which will appear as the description proceeds, the invention consists of certain 20 novel details of construction and combinations of parts which will be hereinafter more fully described and pointed out in the claim it being understood that various changes 25 may be made in the construction and arrangement of the parts without departing from the spirit or sacrificing any of the advantages of the invention as set forth in the appended claim.

In the accompanying drawings the preferred form of the invention has been shown.

In said drawings

Figure 1 is a view partly in plan and partly in section of apparatus including the present improvements.

Fig. 2 is a section on line 2—2, Fig. 1.

Fig. 3 is a section on line 3—3, Fig. 1.

Referring to the figures by characters of reference, 1 designates a water conduit provided at its ends with gates 2 and 3 and 40 opening into the conduit near one end is a feed pipe 4. Another conduit 5 is spaced from and parallel with the conduit 1 and has end gates 6 and 7, the two conduits being connected by cylindrical casings 8, 9 and 45 10 in each of which are arranged turbine wheels 11, 12 and 13 respectively. These wheels are secured to shafts 14, 15 and 16,

respectively, provided with drive wheels 17 at the ends thereof. A gate 18 is arranged in the conduit 5 between the ends of the casings 8 and 9. The gates 3, 7 and 18 are readily movable while the gates 2 and 6 are preferably fixed. A movable gate 19 is in conduit 1 between casings 9 and 10. When the apparatus is not in use, the gates 3 and 19 can be opened and the water entering the inlet 4 will pass through the conduit 1 to the open end thereof. By closing the gate 3 and opening the gate 7 the water will be deflected through the casing 8 and out of the open end of the conduit 5, thereby rotating the wheels 11, and driving the shaft 14. By then closing the gate 19 the water will pass through the casings 10, 9 and 8 successively and by closing gate 7 and opening gate 3 60 the water will pass only through the casings 10 and 9, leaving the wheels 11 stationary. By closing the gate 3 and opening the gates 18 and 7 the water will pass solely through the casing 10, provided the gate 19 is closed. 70 Thus it will be seen that the operation of the parts can be controlled at will.

What is claimed is:—

In a water motor parallel conduits, casings connecting the conduits, turbines within each casing, a water inlet pipe opening into one end portion of one of the conduits and opposite the end of one end casing, a gate within said conduit between said end casing and an intermediate casing, a gate within the other conduit between the other end of the intermediate casing and the other end casing, that end of the intake conduit nearest the inlet being closed, a gate at the other end of said conduit, and a gate at the corresponding end of the other conduit, the other end of the last named conduit being closed.

In testimony that I claim the foregoing as my own, I have hereto affixed my signature in the presence of two witnesses.

JOSEPH HAVLINA.

Witnesses:

W. A. VON BERG,
H. C. MAYNARD.
